PRECAST CONCRETE STEP

Benjamin E. Buffaloe, Memphis, Tenn., assignor
of one-half to Morris L. Beutel, Memphis, Tenn.

Application March 30, 1933, Serial No. 663,625

6 Claims.

(Cl. 72—96) This invention relates to precast concrete steps which are designed for outdoor use although not restricted to such location. Steps constructed as set forth herein, because of the simplicity of the design and the economical advantages in manufacture and use, are particularly adapted for use as ground floor steps for tenement houses, factories and rear steps for any priced home.

As will appear from the detailed description of the invention a stair, or set of steps, is made up of two carriages or jacks cast from concrete and having the usual treads and risers. The step elements or treads are simple concrete slabs laid on the tread surfaces of the carriages or jacks and attached thereto by means of reinforcing rods projecting from the tread surfaces into openings in the step elements and cemented or grouted therein.

The carriages are cast of concrete in a single piece of an open center triangular form. The base of the triangle rests upon the ground or on a suitable concrete foundation, the upright member of the triangle supports the upper end of the third side which constitutes a stringer for supporting the steps and is cast to provide tread surfaces for slabs to rest on.

For a stair of any selected number of steps only two molds are necessary in making, one for the jacks or carriages and one for the step or tread members. The treads are therefore uniform and the carriages may be cast for any number of treads up to about ten above which number the economic value practically ceases.

Referring to the drawing, which is made a part of this application and in which similar reference characters indicate similar parts:

Fig. 1 is a view in perspective of a construction showing four steps.

Fig. 2 is a view of one of the carriages or jacks shown in perspective.

Fig. 3 is an end view of a set of steps as shown in Fig. 1, with a part broken away to the reinforcing rod which fastens the tread to the jack.

Fig. 4 is a perspective view of one of the steps or treads shown in inverted position and,

Fig. 5 is a detail view in section showing the method of attaching the treads to the jacks.

In the drawing the jacks or carriages indicated at 1 are of unitary or monolithic construction being cast of concrete in a suitable mold. These jacks comprise a base portion 2, a vertical portion 3 and an inclined portion 4, which portions define a central triangular opening. This open construction contributes to lessening weight as well as saving material when more than two

steps are involved in a structure as the number of steps increase reinforcing rods in the jacks may be used to give the proper strength without detracting from the appearance of the structure. The member 4 of the jack is provided with a plurality of tread surfaces 5 and risers 6.

As indicated above the jacks or carriages are provided with reinforcement, as indicated by rod 7, Fig. 3. This rod 7 is shown with its central portion disposed in the inclined member 4 of the carriage 1 and with its end portions disposed in the members 2 and 3. Additional or other reinforcing means may be employed. The steps or treads are shown at 8 and each has a recessed or depressed portion on the bottom side as indicated at 9, Fig. 4, which gives a strong and comparatively light construction. The treads are provided with frusto-conical openings near their ends which are suitably spaced to come directly over the tread portions 5 of the jacks when the treads 8 are placed thereon in assembly. These openings 10 have their larger ends upon the upper surface of the treads and when the treads are in place on the jacks the smaller ends of the openings 10 will be closed by the tread surfaces 5.

Referring now to the means for attaching the treads to the stringers 4 of the carriages, reference may be had to Figs. 3 and 5 in which the reinforcing rod or stud 11 is shown attached to the rod 7 as by a half turn therearound and wrapped with wire as at 12. This rod 11 extends upwards through the tread surface 5 a distance less than the thickness of a step 8 and has its upper end bent over, distorted or enlarged as shown at 13 to form a head or enlargement which is embedded in cement or grouting 14 packed in the opening 10 in assembly. The small end of the frusto-conical opening is of sufficient size to pass over the upper end 13 of the rods 11 and being larger than the rods 11 admits of adjustment of the step 8 endwise for alignment of the ends of the steps and also for adjustment with respect to the risers 6 to properly position the steps on the carriages. In placing the steps in position on the carriages a thin layer of cement 15 is spread on the tread surface 5, and on the riser surface 6 as high as the step 8 will extend. This layer of cement serves not only to attach the steps to the carriages but also to compensate for inaccuracies in the castings and insures continuous contact of the treads with the entire tread surfaces 5.

In Fig. 1 the dash lines indicate that portion

of the structure below ground level in out door construction. In this figure the portion 2 rests on a concrete base 16 which is poured in place after the carriages have been assembled in position on temporary blocks.

In assembling the structure described the carriages are placed in position in parallel or temporary blocks and the concrete bases poured under the portions 2 as indicated in Fig. 1. 10 This operation may be made very quickly by using quick setting cement in the concrete for the bases 16. The layers 15 of cement are then applied as indicated in Fig. 5. The slabs or treads 8 are next placed in position with the ends 13 of rods 11 extending into the openings 10. The treads may be properly aligned at their ends by adjustment permitted by reason of the difference in size of the openings 10 and the rods 11. The treads may also be adjusted 15 in position with respect to the risers 6. The cement 15 ensures continuous contact between the treads 8 and the surfaces 5. When the treads are in position grouting or cement is packed in the openings 10 from the top and is leveled off even with the upper surface of the tread providing a continuous cement tread surface, and securely locking the treads to the carriages through the rods 11 which rods also serve to reinforce the stringers 4.

20 The construction described is simple in line, economical in manufacture and enduring in use. Only one mold is needed for the treads of a given design, and only one mold is necessary for the carriages for a selected number of steps. 25 There are only two distinct elements necessary to be cast, the carriage which is used in duplicate and the treads or slab steps of which any desired number may be used. In setting up the steps, the operation is simple and can be rapidly performed. This involves merely setting up the carriages, pouring the concrete bases and putting the step treads in position and filling the 30 openings with cement.

What I claim is:

45 1. A stair composed of pre-cast concrete members, comprising a pair of carriages having reinforcing rods disposed therein with the free ends of certain of said rods extending through the tread surfaces of said carriages and distorted to form a head portion thereon, a series 50 of concrete steps having frustro-conical openings therein near their free ends to pass over the head portions of said rods when the steps are placed in position on said tread portions and a filling of concrete in said openings to lock the steps to the ends of the rods.

55 2. A stair composed of pre-cast concrete members, comprising a pair of reinforced jacks hav-

ing an open center and the usual treads and risers, a reinforcing rod disposed in the base, upright and inclined portions of each jack, a series of reinforcing studs attached to said rod and extending therefrom through the treads of said inclined portion of the jack, the free ends of said studs being distorted to form a head, a series of steps disposed on the said treads and having openings therein for reception of the heads of said studs, and a concrete filling in said 10 openings to lock the steps to the studs.

3. In a concrete stair construction a pre-cast carriage having a base portion, an upright portion and an inclined portion provided with the usual treads and risers, all cast in one piece with an open center, said inclined portion provided with reinforcing means comprising a reinforcing rod and a plurality of reinforcing studs attached thereto, said studs extending from said rod through the surfaces of the treads and distorted at their free ends.

4. In a concrete stair construction, a pair of pre-cast carriages, having the usual treads and risers, rods with distorted ends fastened in said carriages and a series of steps of cast concrete 25 having openings therein to cooperate with the rod ends and disposed on the treads of the carriages and a filling of concrete in said openings and surrounding the distorted ends of said rods and permanently attaching said steps to said 30 treads.

5. In a concrete stair construction, a pair of pre-cast carriages having the usual treads and risers, rods with enlarged head portions cast in the tread portions of said carriages and a series 35 of concrete steps having openings extending through the entire thickness of the step near the free ends of the steps, said openings being adapted to pass over the head portions of said rods when the steps are placed in position on said tread portions and a filling of concrete in said openings to lock the steps to the head portions of the rods.

6. In a concrete stair construction, a pair of pre-cast carriages having the usual treads and 45 risers, rods with enlarged head portions cast in the tread portions of said carriages and a series of concrete steps having openings extending through the entire thickness of the step near their free ends to pass over the head portions of 50 said rods when the steps are placed in position on said tread portions and a filling of concrete in said openings to lock the steps to the head portions of the rods, said head portions extending into the step a distance less than the thickness of the step.

BENJAMIN E. BUFFALOE.
